UNITED STATES PATENT OFFICE.

FRANK J. KROMENAKER AND GRANT M. KROMENAKER, OF CHICAGO, ILLINOIS.

ROOFING.

Application filed September 12, 1921, Serial No. 500,157. Renewed November 4, 1922. Serial No. 599,148.

To all whom it may concern:

Be it known that we, FRANK J. KROMENAKER and GRANT M. KROMENAKER, both citizens of the United States, residing at 5 Chicago, in the county of Cook and State of Illinois, have invented certain new and useful Improvements in Roofing, of which the following is a specification.

This invention relates to a roofing made 10 from material in sheet form, and is particularly concerned with the construction of the several sheets by which they are adapted to interlap so as to provide a rain-proof roofing.

15 An exemplification of this invention is shown in the accompanying drawings where-
in—

Figure 1 is a plan view of several sheets of roofing material in interlapped relation;

20 Fig. 2 is a plan view of a single sheet;

Fig. 3 is an enlarged detail in longitudinal section taken on line 3—3 of Fig. 1;

Fig. 4 is an enlarged detail in transverse section taken on line 4—4 of Fig. 1; and

25 Figs. 5 to 8 inclusive are views similar to Figs. 1 to 4, respectively, showing roofing sheets of slightly altered proportions.

Our invention contemplates the employment of a suitable roofing material in sheet 30 form properly prepared to withstand the usual weather conditions encountered in use. The sheets which form the roofing are adapted to be fastened as by means of nails to a slanting roof in much the same way as is usual with other roofing materials having 35 similar properties.

In Fig. 2 we have shown a section of roofing material which, for purposes of convenience in handling and installation, is in the 40 form of a rectangular sheet. Slits 10 are cut through the sheet from one of its longer edges 11 to a distance which is more than midway toward the opposite edge 12 and in the construction shown in Figs. 1 to 4, these 45 slits are arranged in groups of two so as to provide tongues 13 between which lie what may be termed slabs 14. The sheet edge 12 may be provided with notches 15 located substantially midway between the tongues 13, as best shown in Fig. 2. It will be noted 50 that the positions of the tongues with relation to the sheet is preferably such that a portion of a slab is left at each end of the sheet. Half notches 16 may be provided at 55 the extremities thereof. The purpose of this is to facilitate corelating of the sev-

eral sheets which, when properly interlapped, constitute the roofing of our invention.

In Fig. 1 we have shown three full sheets 60 properly related to form the roofing. The under sheet is designated as A. The slit edge of this sheet, however, lies beneath a second sheet B and a third or upper sheet C. The upper and lower edges of these last two 65 sheets are designated as 11^b and 11^c and 12^b and 12^c, respectively. The ends of sheet B are aligned with the centers of two of the tongues 13 of sheet A, all of the tongues thereof being lapped over the sheet B, as 70 shown. The distance of overlap of sheet B upon sheet A is determined by the length of the several tongues 13 which, as already explained, are preferably slightly more than half the width of each sheet. In like manner the third sheet C is arranged over sheets 75 A and B, being aligned with the ends of sheet A.

In arranging the roofing sheets as above explained, a permanent fastening may be 80 obtained with nails 20 which, by preference, are driven through the tongues 13 adjacent their free ends. When so secured, the lower edge of the sheet C will overlie the proximate edge of sheet A and the nails driven 85 therethrough so that the tongue ends where in the nails are secured are completely covered. It follows, therefore, that this construction provides a protection for the nails, such as to thoroughly conceal their presence. 90 A realization of the advantages just set forth results from forming each roofing sheet so as to overlie the one therebeneath by something more than half its width, from which it follows that the first sheet is 95 also overlapped in part by a third sheet.

In Figs. 5 to 8 inclusive, we have shown 100 a similar construction, the only difference being that instead of forming slits 10 in groups of two, we have arranged them equidistantly apart, with the result that the tongues and slabs are of the same size. The same numerals are applied to the several parts of these figures, and consequently no further description thereof is deemed to be 105 necessary. The principal difference is in the optical effect, but since the underlying principles of the two constructions are the same, such differences as exist are purely inconsequential.

110 From the preceding description, it is to be observed that our invention involves al-

most no additional expense other than for the slitting of roofing sheets in a particular manner so that they may be correlated to provide a tight roofing. No special skill or expenditure of labor or time is required other than what is ordinarily necessary with elaborated roofings. In addition, the several tongues serve to hold down the lower edges of each roofing sheet so as to prevent the same from curling upwardly, and this is a positive advantage not realized by the different roofings with which we are familiar. Manifestly the principles of our invention are susceptible of embodiment in forms other than herein shown, and in respect of any modifications which utilize the principles hereinbelow claimed, it is desired that the same be included within the scope of this patent.

20. We claim:

1. As a new article of manufacture, a rectangular sheet of roofing material provided with slits which extend from one of its edges more than half way towards an opposite edge thereof.
2. As a new article of manufacture, a rectangular sheet of roofing material provided with slits which extend from one of its longer edges more than half way towards its opposite edge, the slits being arranged in groups of two to define tongues and slabs in alternating relation.
3. As a new article of manufacture, a rectangular sheet of roofing material provided with slits extending from one of its longer edges more than half way towards its opposite edge, the several slits defining tongues and slabs in alternating relation arranged along one edge of the sheet.
4. A roofing comprising in combination a plurality of similar rectangular sheets each provided with a plurality of slits extending from one of its longer edges more than half way towards the opposite edge to define tongues said slabs in alternating relation, the adjacent sheets being laid side by side, and laid in staggered overlapping courses, so that each sheet is covered in part by each of two ensuing courses, with the tongues overlapping the sheets a distance equal to the length of the slits, and the extremities of the tongues being arranged to underlap the sheets of the second ensuing course.

5. A roofing comprising in combination 55 a plurality of similar rectangular sheets each slitted transversely to provide tongues and slabs in alternating relation, the several sheets being laid side by side and laid in staggered overlapping courses, so that each sheet is covered in part by sheets of each of two ensuing courses, with the tongues arranged to overlap the sheets of the first ensuing course, means passing through the tongue extremities for securing the sheets 60 to a support, the overlapping sheets in the second ensuing course being disposed in covering relation to the tongue extremities thereby to conceal said securing means.

6. As a new article of manufacture, a 70 sheet of roofing material provided on one edge with alternate tongues and slabs adapted to be laid with the tongues to extend over and the slabs under the next higher adjacent sheet.

7. As a new article of manufacture, a sheet of roofing material provided on one edge with alternate tongues and slabs adapted to be laid with the tongues to extend 75 over and the slabs under the next higher adjacent sheet, said tongues being longer than one half the width of the sheet measured in the direction of the length of a tongue.

8. As a new article of manufacture, a 85 sheet of roofing material provided with tongues and slabs arranged on one edge of the sheet.

9. As a new article of manufacture, a 90 substantially rectangular sheet of roofing material provided with pairs of slits extending from one of the longer edges toward the opposite edge to provide alternate tongues and slabs arranged on one edge of the sheet.

10. As a new article of manufacture, a 95 substantially rectangular sheet of roofing material provided with pairs of slits at right angles to the length of the rectangular sheet and extending from one of the longer edges toward the opposite edge to provide alternate tongues and slabs arranged on one edge of the sheet.

FRANK J. KROMENAKER.
G. M. KROMENAKER.
